UNITED STATES PATENT OFFICE.

JOSEPH FREDRICK LAMB, OF NEW BRITAIN, CONNECTICUT, ASSIGNOR TO LANDERS,
FRARY & CLARK, OF NEW BRITAIN, CONNECTICUT.

ELECTRICAL CONTACT DEVICE.

1,217,964.

Specification of Letters Patent.

Patented Mar. 6, 1917.

Application filed June 23, 1916. Serial No. 105,386.

To all whom it may concern:

Be it known that I, JOSEPH FREDRICK LAMB, a citizen of the United States, residing at New Britain, in the county of Hartford and State of Connecticut, have invented certain new and useful Improvements in Electrical Contact Devices, of which the following is a specification.

My invention relates to improvements in electrical contact devices, and the object of my improvement is to produce a socket contact device suitable for use with cord connections for making electrical connection with a plug contact for the supply of current to articles for household use, and which will serve to make a connection that will be operative and satisfactory under the various conditions that prevail in the class of service mentioned, involving simplicity and economy in construction and convenience and efficiency in use.

Socket contact devices of the class to which my invention applies are made of sheet metal, bent into generally tubular form, and as evolved in my invention the socket contact device is of triangular form of cross-section, one side wall serving as the main contact member for extending along the plug and the other two side walls serving as holding members for holding the said main member in such contact, and this result is obtained in a more reliable and superior manner by avoiding any gap in the said holding members in the portions of the said holding members that are directly opposed to the main member and by locating the gap between the opposed free edges of the blank so that the said gap will be positioned along one edge of the main member.

40 In the accompanying drawing;—

Figure 1 is a plan view of a complete socket member provided with a pair of sockets and a cord connection, embodying my invention.

45 Fig. 2 is an end elevation of the same.

Fig. 3 is a plan view of the parts shown in Fig. 1, with one of the shell members removed.

Fig. 4 is a sectional view on the line $\alpha\alpha$ of Fig. 1.

50 Fig. 5 is an end elevation of the plug member.

Fig. 6 is a plan view in part broken away of the same.

Fig. 7 is a plan view of the blank for one of the sockets.

Fig. 8 is a side elevation of the socket member complete.

Fig. 9 is an end elevation on an enlarged scale of the same.

Fig. 10 is a sectional view on a reduced scale, on the line $y\gamma$ of Fig. 9, the plug being shown in position.

Fig. 11 is a sectional view on the line $z\zeta$ of Fig. 8, and on an enlarged scale.

The complete contact device shown in the drawing comprises a pair of my improved socket contact devices 10, in spaced relation, suitable for cooperating with a pair of plug contacts 11, in corresponding spaced relation and rigidly secured within a suitable support; such as the shell-like casing 12, the said socket contact devices or sockets 10 being contained in a housing like that shown in the patent to Alonzo A. Warner, No. 75 1,059,650, April 22, 1913.

The said housing is made of insulating material and comprises a pair of mating shell members 13 and 14 having opposed faces in abutment, held together by a pair 80 of screws 15, and having cooperating grooves 18 for containing the sockets 10, and the duplex cord 17 connected to the sockets 10 by the individual branches or members 16.

One end of each socket 10 is connected to 85 the branch cord 16 by means of a terminal screw 19. The active portion 22 of the socket 10 extends from adjacent the terminal screw 19 outwardly to the other end, the same being of triangular form of cross-section and housed in a portion 20 of the grooves or cavities 18 of corresponding form.

The socket 10 is formed of sheet metal, the blank therefor being shown in Fig. 7. The said blank is approximately rectangular, 95 and comprises along one edge the body portion 21 of proper width and length to form one side or the base of the triangular active portion 22, and also to extend inwardly suitably to receive the terminal screw 19. 100 A plurality of fingers extend outwardly to one side from one edge of the base 21, comprising the finger 23 at the terminal end and a set of other fingers 24. The finger 23 is shorter than the other fingers, being of sufficient length to be turned back by a return bend, as shown at 25, Fig. 11, so as to cover the terminal end portion 26 of the base 21, 105

and serve as a reinforcement thereof. After being bent into position as mentioned, a hole 27 is punched through the double thickness of material from the upper side, through the finger 23 and the terminal end portion 26, material from the hole being carried through along the border walls as shown at 28, thus providing surplus length for the border wall of the said hole 27 and for the 10 screw thread that is provided therein for the terminal screw 19.

A cap of channel form is provided for co-operating with the screw 19 for housing and securing the strands of the cable or cord 16 15 comprising the body portion 29 of rectangular or square form with a central hole for receiving the screw 19 and a pair of dependent flanges 30 at the edges, fitting and extending along the edges of the double 20 thickness terminal, 23, 26, the cable being housed in the spaces 31 between the screw 19 and the said flanges 30.

The fingers 24 serve as contact fingers, and are of sufficient length to form the other 25 two sides of the triangular active portion 22, the cross-section of the same being approximately equilateral, there being in the finished socket 10 a small open, free space between the free end portions 32 of the contact fingers 24 and the opposed edge of the base 31. The two corners of each of the 30 said free end portions 32 of the contact fingers 24 are clipped, as shown at 33, whereby the said free end portions 32 are generally of 35 tapered form.

As stated, the sockets 10 are made of sheet material, and the same is of sufficient strength so that when used in pairs as described the combined weight of the connected parts, consisting of the shell members 40 13 and 14 and the cable end 17, will be positively supported by the engagement of the two sockets 10 with the two contact pins 11, and such positive support is provided even 45 when the sockets 10 are only partially entered on the pins 11, such as when only the outermost contact fingers 24 are engaged with the pins 11. Such support is furthermore provided independent of the inclosing 50 housing provided by the shell members 13 and 14.

Accordingly, each contact finger 24 combines with the base 21 to form a complete individual connecting socket, independent 55 of the other adjacent finger 24. The advantage of this arrangement is that under normal conditions of use, with all the contact fingers 24 engaged with the pins 11, each of the said individual sockets is active, and 60 they all coöperate to deliver current, a condition that is especially desirable for certain household implements that require an appreciable quantity of current,—imperfect contact increases the drop and causes excessive heating of the contacts.

Furthermore, by providing for a plurality of individual contact sockets as described the condition of maximum active contact described pertains even with slight inaccuracies in the contact pins 11, such as are 70 liable to occur when such contact pins 11 are produced commercially in large quantities. For instance, the pins 11 are supposed to be of cylindrical form for the active portion, whereas actually they may 75 be slightly tapered, to the extent of a small fraction of an inch. Notwithstanding this condition the plurality of individual sockets provided as described always insures a proper and full contact.

Considering the feature of the triangular form of the active portion 22, and particularly the individual sockets of which the same is composed, it will be noted that the contact points are distributed around the periphery of the pins 11 at essentially equidistant points or lines. The fingers 24 are set so that a slight opening out of the socket is required in slipping the socket along the pin 11, and because of the triangular relation, all of the sides of the triangle are active, and they adjust themselves under the pressure due to the resiliency of the material, so that all are held in engagement with the pin by the same contact pressure. The 95 socket 22 as described is formed by folding a sheet metal blank, leaving a small free open space between the opposed edges of the blank. It will be noted that I have so formed the blank and folded the same that 10 the said opening is provided along one edge of the flat base or main member 21, between the said edge and the ends 23 of the fingers 24, and in lieu of an open space directly opposed to the main member 21 there is a 11 closed hook-like formation of the fingers 24. Thus the fingers 24 are adapted to serve as holding members to hold the main member 21 in contact with the portion of the plug opposed thereto, whether fully or only 12 partially entered on the plug, and notwithstanding any relative shifting or twisting of the plug and socket so as to be out of alignment such as may be effected by the weight of the cord or by movements of the 13 operator, particularly in such devices as sad-irons.

The clipping of the corners 33 adds to the flexibility of the contact fingers 24 and facilitates the engagement thereof with the pins 11, particularly in case of slight inaccuracies of alignment of the sockets 10 and the pins 11 as they are brought into engagement.

As described, the finger 23, connected to 1 the terminal extension 26 of the base 21 by a return bend, is superimposed on the said extension 26 and serves as a reinforcing layer, and the said layer and extension as a unit are provided with a threaded hole for a 1

terminal screw, and material from the said layer and extension forming the border walls of the said hole is extended axially so as to extend the screw threaded wall below the face of the said extension. Thus material of the said layer overlaps material of the said extension and the overlapping portions are forcibly interlocked, one with the other.

10 I claim as my invention:—

1. A socket for a plug connection formed from a blank of sheet metal, bent into tubular form, comprising in combination a main member in the form of a flat

15 spring suitable for extending along one side of the plug, and being extended longitudinally to provide means for receiving a terminal connection, a plurality of fingers opposed to the said main member, serving as holding members for holding the said main member in contact with the plug, the said fingers extending continuously over the face of the said main member, being bent to form the other two sides of the said socket, being each connected by one end to one edge of the said main member, and the other ends of the said holding members being opposed to the other edge of the said main member and separated therefrom by an open space.

20 2. A blank for a contact socket made of sheet metal of approximately rectangular form, comprising a continuous strip along

one side, and having fingers extending laterally from one edge of the said strip toward the other side, one of the said fingers 35 being at one end and of suitable length to be turned back by a return bend against the said strip to reinforce the same, and the others of the said fingers comprising a set of similar fingers of suitable length to be 40 bent individually transversely and to be positioned by a bend at the junction with the said strip to form with the said strip a contact socket of triangular cross-section.

3. A socket connecting member for a plug 45 connection made of sheet material, comprising a socket portion composed of a base and a plurality of contact fingers connected to the said base, an extension of the said base serving as a terminal portion, the said extension being reinforced by a superimposed 50 layer of material connected by a return bend, the said layer and extension being provided with a threaded hole for a terminal screw, and the material of the said layer and extension forming the border walls of the said hole being extended axially so as to interlock the said layer and extension and to extend the screw threaded wall below the face of the said extension.

JOSEPH FREDRICK LAMB.
